UNITED STATES PATENT OFFICE.

JAMES A. CRUMLEY, OF CHARLESTON, WEST VIRGINIA, ASSIGNOR OF ONE-THIRD TO
ELVYN L. KELLER, OF CHARLESTON, WEST VIRGINIA.

BULL WHEEL AND MOUNTING THEREFOR.

Application filed September 20, 1923. Serial No. 663,934.

To all whom it may concern:

Be it known that I, JAMES A. CRUMLEY, citizen of the United States, residing at Charleston, in the county of Kanawha and 5 State of West Virginia, have invented certain new and useful Improvements in Bull Wheels and Mountings Therefor, of which the following is a specification.

This invention relates to certain new and 10 useful improvements in bull wheels and mountings therefor, such as are employed in connection with the drilling of oil wells and the like.

Objects of the invention are to provide 15 a wheel of the above kind which embraces the desired qualities of simplicity, durability, and efficiency in operation; to provide a bull wheel which may be readily manufactured and assembled as well as repaired 20 at a low cost, and to generally improve and simplify devices of this kind whereby they may meet with all of the requirements for a successful commercial use.

With the above general objects in view 25 and others that will become apparent as the nature of the invention is better understood, the same consists in the novel form, combination, and arrangements of parts hereinafter more fully described, shown in 30 the accompanying drawings and claimed:

In the drawings, wherein like reference characters indicate corresponding parts throughout the several views:

Figure 1 is a front elevational view of 35 a bull wheel constructed in accordance with the present invention.

Figure 2 is a side elevational view thereof.

Figure 3 is an enlarged sectional view taken through the pipe at one side of one 40 of the split hubs with the disc and cants removed.

Figure 4 is a view similar to Figure 3 with the line of section midway between the ends of the split hub.

Figure 5 is a fragmentary longitudinal sectional view of one end of the bull wheel, pipe or drum, with one of the gudgeons therein shown in elevation.

Figure 6 is a view similar to Figure 5 50 with the gudgeon in central longitudinal section.

Figure 7 is an enlarged fragmentary sectional view taken transversely through the discs and cants of one of the heads or wheel members.

Figure 8 is a plan view of one of the split hubs with the sections thereof bolted together preparatory to machining or finishing the surfaces of the same.

Figure 9 is a radial central sectional view 60 of one of the wheel members.

Figure 10 is an enlarged sectional view taken substantially on the line 10—10 of Figure 1 to illustrate the flyer construction, the latter being partly in section. 65

Figure 11 is a side elevation of one of the mountings for the bull wheel.

Figure 12 is an enlarged section on the line 12—12 of Figure 11, partly broken away, and 70

Figure 13 is an elevation of one of the mounting bearings.

Referring more in detail to the drawings, the present invention embodies a drum or pipe section 5 upon the ends of which are 75 mounted the wheel members 6 and 7.

Each of these wheel members comprises a split hub composed of similar longitudinal half sections 8 that are preferably cast and provided with bolt receiving flanges 9 midway between their ends adapted to receive the bolts 10 whereby the hub sections are securely clamped together to facilitate machining thereof. These split hubs are provided with circumferential spaced and 85 parallel external flanges 11 inwardly from the ends thereof and at opposite sides of the flanges 9 as clearly shown in Figure 8, and the annular flanges 11 are provided with suitable openings 12 for a purpose which 90 will presently become apparent.

Sheet metal discs 13 are disposed upon the ends of the split hub of each wheel member against the outer sides of the annular flanges 11 thereof, said discs being centrally apertured for snug reception of the ends of the hub, and the inner portions of the discs being rigidly fastened to the flanges 11 by bolts 14, passing through both flanges and discs as shown in Figure 9. Each wheel 100 member thus comprises a split hub with spaced parallel disc members fastened thereon, and the outer edges of these discs are connected by means of transverse bolts 15 which also pass through wood cant rings 16, 105 preferably three in number, which are arranged between the margins of each pair of discs as clearly shown in Figures 7 and 9. The only difference between the cants of the two wheel members is that one of the same 110

has the outer two cants thereof circumferentially grooved as at 17 to form tug cants as is well known in the art.

The bolts 15 are of considerably greater length than the combined widths of the discs 13 and cants 16, and spacer sleeves 18 are disposed upon the projecting ends of said bolts between the heads of the same and the adjacent disc 13, thus providing 10 the side circular series of pins or handles used upon wheels of this character.

The other ends of the bolts 15 have nuts 19 threaded thereon, whereby the discs and cants are rigidly bolted together.

15. Gudgeons are secured within the ends of the pipe section 5 and each of the same embodies an integral device, the inner end portion of which is relatively large and shaped as at 20 to have a snug ordinary fit within 20 said pipe section, and the outer end of which is of reduced size and of cylindrical form as at 21, for cooperation with a suitable bearing whereby the bull wheel may be rotatably mounted. The outer end of the larger 25 gudgeon portion 20 is provided with a circumferential annular flange 22 adapted to abut against the end of the pipe section 5 so as to provide a more rigid and durable construction. The central portion 21 of each 30 gudgeon may be connected with the portion 20 thereof by means of integral radial webs or spoke members 23 as shown in Figure 2, and the gudgeons are preferably fastened in place by riveting as at 20^a.

35. In assembling a bull wheel of the above construction, the pipe section 5 is drilled with the proper holes, and then the gudgeons are fitted and riveted in place. Then the discs 13, cants 16, and hub 8 are assembled 40 by bolting at 14 and 15, the bolts 15 being drawn tight and the bolts 14 being left loose for allowing the hub section to separate so they can be slipped onto pipe 5. The hubs are then securely bolted to pipe 5 by 45 a pair of crossed bolts at each end of each hub as at 24, and then the bolts 14 are tightened for securing the discs rigidly against the hub flanges 11. The bolts 10 are only used when the hubs are being machined and the 50 flanges 11 are braced against the action of bolts 14 by the ears or flanges 9 and transverse ribs 25 connecting the flanges 11 between the flanges 9.

A novel form of flyer 26 is mounted on 55 the pipe 5 between the heads 6 and 7 so as to divide the wheel into two portions, respectively, upon which may be wound the slack portion of the cable and the portion of the latter which is actually in use, as 60 is well known in the art. This flyer embodies a plurality of reeling arms disposed tangentially of the pipe 5 and each including an inner section 27 of channel iron and an outer section or bar 28, preferably of

wood and pointed or tapered as at 29 at 65 their outer ends. The flanges of the sections 27 are directed outwardly and the webs thereof disposed against the pipe 5, the inner ends of sections 27 being closed as at 30 and abutting against the webs of each 70 other. The inner end portions of the outer arm sections are positioned within the inner arm sections and are secured in place by bolts 31 and 32, each bolt 32 being passed through the inner ends of a pair of opposed 75 arms and the pipe 5, entering both sections of said arms. The bolts 31 are provided in pairs, each pair passing through the sections of one arm and the inner end wall 30 of the arm abutting against the side thereof. 80

The bull wheel above described is rotatably supported by a special mounting consisting of a pair of posts, one arranged at each end of the wheel and each having a bearing for reception of one of the gudgeon 85 portions 21. As shown in Figures 11 to 13, each post consists of a piece of pipe 33 notched at one side of its lower end as at 34 to form a seat for the derrick floor sill 35 which is of channel form and disposed 90 with its flanges horizontal and projecting outwardly, the notch being on an incline so that the post will occupy an inclined position, and the sill being secured to the post by a bolt 36 passed through the web of the sill and through the post. A circular opening is formed in a side of the post 33 as at 37 for snug reception of a long hollow boss 38 formed on one side of a bearing plate 39, the inner side of which is concaved to 100 fit against the post as at 40. The plate 39 projects above and below the opening 37 and has openings 41 through which bolts 42 pass, the bolts 42 passing through the post for rigidly securing the bearing plate thereto. 105 The plate 39 has a transverse opening 43, the wall of which is lined as at 44 by durable bearing metal, and said opening forms the bore of the boss 38 and the bore of a short boss 45 formed on the outer side of 110 the plate 39. A lug 46 is formed on one side edge of plate 37 and this lug has a passage that opens at the top thereof and that communicates with an inclined passage through the adjacent portion of the plate and the lining 44 as at 47. Means is thus provided for facilitating oiling of the gudgeon portions 21 disposed in the openings 43 of the respective bearings. The upper ends of the posts 33 are slotted or bifurcated as at 48 for reception of the ends of a tie or brace rod 49 which is secured in place by a U-bolt 50 passing through one leg of the bifurcation and around said rod. 115 From the above description it will be seen 120 that I have provided a very simple and durable form of bull wheel and mounting which may be cheaply and easily manufactured 125

and placed in use, and which may be repaired from time to time if found necessary, with facility and ease.

Minor changes may be made without departing from the spirit and scope of the invention as claimed.

What I claim as new is:

1. In a bull wheel, a pipe section having gudgeons secured in the ends thereof, split hubs detachably bolted upon the ends of said pipe section, said hubs being provided with pairs of spaced parallel circumferential annular flanges, discs disposed upon the end portions of the hubs and detachably and rigidly secured against the outer surfaces of said annular flanges, and cants bolted between the outer margins of said discs.
2. In a bull wheel, a pipe section having gudgeons secured in the ends thereof, split hubs detachably bolted upon the ends of said pipe section, said hubs being provided with pairs of spaced parallel circumferential annular flanges, discs disposed upon the end portions of the hubs and rigidly secured against the outer surfaces of said annular flanges, cants bolted between the outer margins of said discs, said bolts being of greater length than the combined widths of the cants and discs, so as to leave ends thereof projecting, and spacing sleeves between the heads of the bolts and an adjacent disc upon the projecting ends of said bolts.
3. In a bull wheel of the character described, the combination of a drum in the form of a pipe section having heads upon the ends thereof, a flyer attached to the drum between said heads and comprising a plurality of tangential reeling arms with their inner end portions disposed against the drum and securely bolted to the latter in pairs, said reeling arms each having its inner end abutting against the side of an adjacent arm and bolted to the latter, each of said arms comprising an inner arm section of channel form with outwardly directed flanges and an outer arm section in the form of a bar with its inner end portion disposed within the inner arm sections thereof and secured to the latter by the bolts utilized to secure the arms to the drums and to each other.
4. In a bull wheel of the character described, the combination of a drum in the form of a pipe section having heads upon the ends thereof, a flyer attached to the drum between said heads and comprising a plurality of tangential reeling arms with their inner end portions disposed against the drum and securely bolted to the latter in pairs, said reeling arms each having its inner end abutting against the side of an adjacent arm and bolted to the latter, each of said arms comprising an inner arm section of channel form with outwardly di-

rected flanges and an outer arm section in the form of a bar with its inner end portion disposed within the inner arm sections thereof and secured to the latter by the bolts utilized to secure the arms to the drums and to each other, the inner arm sections having inner end walls through which extend the bolts for securing the arms to each other.

5. In combination with a bull wheel including a drum having heads secured upon the ends thereof and gudgeons secured in the ends of said drum with reduced projecting outer ends, tubular posts having means at the lower ends thereof for facilitating rigid attachment of the same to the derrick floor sill of a well drilling apparatus, said posts having openings in the inner sides thereof between their ends, and bearing plates for reception of the reduced projecting ends of the gudgeons bolted to said posts, said bearing plates having inwardly extending hollow bosses projecting into the openings of said posts.

6. In combination with a bull wheel including a drum having heads secured upon the ends thereof and gudgeons secured in the ends of said drum with reduced projecting outer ends, tubular posts having means at the lower ends thereof for facilitating rigid attachment of the same to the derrick floor sill of a well drilling apparatus, said posts having openings in the inner sides thereof between their ends, and bearing plates for reception of the reduced projecting ends of the gudgeons bolted to said posts, said bearing plates having inwardly extending hollow bosses projecting into the openings of said posts, said bearing plates further having side lugs, and passages in the lugs and plates for facilitating oiling of the projecting gudgeon portion.

7. In combination with a bull wheel including a drum having heads secured upon the ends thereof and gudgeons secured in the ends of said drum with reduced projecting outer ends, tubular posts having means at the lower ends thereof for facilitating rigid attachment of the same to the derrick floor sill of a well drilling apparatus, said posts having openings in the inner sides thereof between their ends, and bearing plates for reception of the reduced projecting ends of the gudgeons bolted to said posts, said bearing plates having inwardly extending hollow bosses projecting into the openings of said posts, the means for facilitating attachment of the lower end of each post to the derrick floor sill embodying the provision of a notch in the inner side of the lower end of each post for seating reception of the derrick sill, and bolts passing through the web of the sill and the post for rigidly securing the latter together.

8. In combination with a bull wheel in-

cluding a drum having heads secured upon the ends thereof and gudgeons secured in the ends of said drum with reduced projecting outer ends, tubular posts having means at the lower ends thereof for facilitating rigid attachment of the same to the derrick floor sill of a well drilling apparatus, said posts having openings in the inner sides thereof between their ends, and bearing plates for reception of the reduced projecting ends of the gudgeons bolted to said posts, said bearing plates having inwardly extending hollow bosses projecting into the openings of said posts, the means for facilitating attachment of the lower end of each post to the derrick floor sill embodying the provision of a notch in the inner side of the lower end of each post for seating reception of the derrick sill, and bolts passing through the web of the sill and the post for rigidly securing the latter together, said notch being formed on an incline whereby the post assumes an inclined position when bolted to the sill.

9. In a bull wheel, a drum having heads secured upon the ends thereof, each of said heads embodying a hub composed of longitudinally split half sections, means including a pair of cross bolts passing through each end of each of the hub sections and thru the drum for securing the hubs in said drum, cant rings surrounding the hub and rigidly secured to the latter, said hub sections having outwardly directed mating fingers adapted to be bolted together for facilitating the machining of said hub, spaced annular rigid flanges formed externally upon said hubs inwardly of the ends thereof, the means for rigidly connecting the cant rings to the hub embodying discs fitted onto the ends of the latter against the outer sides of said annular flanges, and bolts extending through said annular flanges and discs for rigidly securing the same together.

In testimony whereof I affix my signature

JAMES A. CRUMLEY.
